UNITED STATES PATENT OFFICE.

GEORGE COLVIN KENNEDY, OF WATERLOO, IOWA.

MARBLE-GUN.

1,077,142.

Specification of Letters Patent.

Patented Oct. 28, 1913.

Application filed September 23, 1912. Serial No. 721,881.

To all whom it may concern:

Be it known that I, GEORGE COLVIN KENNEDY, a citizen of the United States of America, and a resident of Waterloo, Black-hawk county, Iowa, have invented certain new and useful Improvements in Marble-Guns, of which the following is a specification.

My invention relates to improvements in marble-guns, and the object of my improvement is, first, to provide for that type of marble-guns which have pivotally-mounted sighting-devices, improved and efficient means for releasably retaining such devices 10 in positions in which they may be placed relative to the conduit or barrel of the gun; and second, to furnish foldable handles for the gun, which may be swung up out of the way when desired, or when the gun is arranged to be carried in the pocket.

This invention is an improvement upon my marble-gun, patented to me by the United States of America, on September 3rd, 1912, Number 1,037,262.

The above objects I have carried into effect by the following means as hereinafter described and claimed, and which are illustrated in the accompanying drawings, in which:

Figure 1 is a perspective view of my improved marble-gun, showing it with its sighting-devices erected, and with its hinged handle-bars swung downwardly for use. Fig. 2 is a perspective view of my said gun, showing both the said sighting-devices and the handle-bars swung toward the barrel to lie therealong. Fig. 3 is a rear end elevation of the device shown in said Fig. 1. Fig. 4 is a rear end elevation similar to that shown in Fig. 3, but equipped with a varied fastening-means for the sighting-devices and handle-bars, both said devices and bars being shown broken away. Fig. 5 is a perspective view of a varied form of said marble-gun, with its sighting-devices erect. Fig. 6 is a side elevation of the rear part only of the gun shown in Fig. 5, with parts broken away. Fig. 7 is a rear end elevation of the gun shown in Fig. 5, with a part of the scrolled lower end of the rear sighting-device and of its supports sectioned away. Fig. 8 is a transverse vertical section of the marble gun taken immediately in the rear of its forward sighting-device. Fig. 9 is a rear end elevation of a marble-gun of the type illustrated in Fig. 5, but be-

ing slightly varied in its means for fastening the sighting-device. Fig. 10 is a side elevation of a third varied form of marble-gun, with dotted lines showing the folded-together positions of the sighting-devices and of the pivoted handle-bars, the full lines indicating the extended positions of said parts. Fig. 11 is a rear end elevation of the gun shown in said Fig. 10, with parts of both the sighting-devices and handle-bars broken away.

Similar numerals of reference denote corresponding parts throughout the several views.

Referring to Figs. 1 to 3 inclusive, I have shown a cylindrical tube 1 formed from a flat sheet of metal by bending, and having pairs of integral oppositely-located lugs 2 and 3 located near the rear and forward ends and projecting upwardly and spaced apart to receive therebetween the sighting-devices or bars 6 and 7 respectively. Said lugs and bars are provided with registering orifices in which are seated the rivets 4 and 5 respectively, said rivets being of the so-called "tight-and-loose" variety, that is, being compressed sufficiently upon the lugs to cause the lugs to bear upon the interposed bars or sighting-devices 6 and 7 frictionally 70 to allow the bars to be swung up or down without difficulty, while grasping them tightly enough to hold them in positions in which they are placed as against the exercise of ordinary force upon them. The 75 sighting-devices will then remain in either their erect or recumbent positions when in use, without other fastenings.

The handle-bars 8 and 9 are placed on opposite sides of the rear part of the conduit 1, and are pivoted on the rear rivet 4 outside of the lugs 2, and are medially curved outwardly at 10 so that when swung downwardly they will embrace opposite sides of the conduit frictionally and tightly when 95 held clasped together in the hand. These handle-bars are elastic enough to yield when being swung up or down to pass over the conduit, and spring back to a closed position when lying recumbent upon the conduit, as shown in Fig. 2. It will be noticed, that the sighting-devices 6 and 7 have their pivot rivets so placed in the lugs, that when swung downwardly the device 6 overlies the forward device 7, with both lying 100 between the bars 8 and 9, which renders the whole compact for carriage in the pocket.

The rear end of the conduit may be cut away and projected rearwardly in the form of a trough 13. A vertical slot is cut in the upper side of the rear part of the conduit 1 back of the rear lugs 2, and the looped ends of an elastic body or rubber band 12 may be looped over the arms thus formed to act as propelling-means at the rear end of the gun. When the marble or other missile 10 is placed in the medial loop of said band 12 and both held between a finger and thumb of the user, the sights 6 and 7 being erect and the handle-bars 8 and 9 down and held in the other hand of the user, the object 15 aimed at over the said sights or in line therewith may be hit by the tension and sudden release of the stretched band 12. This is for a drop or distance shot, but for a rolling propulsion of the marble over the ground, 20 the handle-bars may be left up on the conduit, and the latter placed on the ground and moved about with the directing hand of the user till the sights are in line with the object aimed at.

25 In Fig. 4 is shown, instead of the rivet 4, a short bolt 14, upon whose threaded end a thumb-nut 15 works, and which serves to hold the sighting-device 6 tightly in any position in which it is placed, but which 30 may be released by a slight turn to permit of swinging the device up or down. The troughed end 13 serves to prevent a marble or other missile from falling or striking the rear edge of the conduit when released, especially when a drop-shot is being taken.

In Figs. 5 to 8 inclusive are shown a slightly varied device but within the same principles of use. In this form of marble-gun, a seamless tube 1 is used for the conduit, and bands are secured by brazing or 40 the rivets 23 and 31 respectively about its rear and forward ends. The forward band shown in Fig. 8 is really formed of two separated pieces clasping opposite sides of the conduit, and having lower bent legs 45 33 to provide a square seat for the conduit. The upper ends of the bands 32 are projected upwardly to form spaced apart lugs 29 with upper ends bent toward each other 50 but narrowly spaced apart. The sighting-devices are located at 17 and 16 respectively with edges turned laterally and having 55 scrolled lower ends, the scrolls 27 and 19 being movably seated respectively on the bolts 28 and 20 which are in turn seated in alined orifices in the said lugs on both the forward and rear bands 32 and 22. The 60 threaded outer ends of the bolts are provided with wing- or thumb-nuts 30 and 26 respectively, as before mentioned. When the sights are placed in any position, they are held securely by the tension of the nuts upon said lugs and scrolls. The sights, however, are prevented from moving forward 65 or backward of the vertical respec-

tively by engaging the bent over ends of the lugs 29 and 21 at 18. The rear band 22 has similar feet 25, and has side bends at 24, the lower parts of the bands below the bends being left slightly spaced apart from the conduit to permit of the introduction of the looped elastic band 12. Fig. 9 shows the bands 22 adapted to receive a rivet 14 through its upstanding lugs 21 and the interposed sighting-device 6, as first-described herein.

Figs. 10 and 11 illustrate a form of my invention wherein a seamless tube 1 is employed as a conduit, the rear end being cut away obliquely to provide a trough 13, and saw-kerfs 11 and 39 forming narrow passages and receiving slots for the looped ends of the elastic band 12. Bands 34 and 37 are brazed about the rear and forward parts of said conduit and have their upstanding ends 35 and 38 respectively orificed to receive rivets of the kind previously described at 4 and 5 to hold orificed sighting-devices 6 and 7 therebetween in a similar way and for a similar use. The handle-bars 8 and 9 are like those previously described, and are seated about the rear band 34 which they grasp when down. The marble-gun may be used also to propel arrows or other missiles in an obvious way, and when 95 the movable parts are folded down the device is very compact and suitable to be carried in the pocket.

Having described my invention, what I claim as new, and desire to secure by Letters 100 Patent, is:

1. In combination, in a marble-gun, a conduit, a sighting-standard movably mounted thereon, means for releasably retaining said standard in a desired position relative 105 to the conduit, one end of said conduit being cut away for a distance at its top to form a missile upholding trough under the propelling-means, and elastic propelling-means connected to the same end of said conduit 110 along said trough.

2. In combination, in a marble-gun, a conduit, and a pair of handle-bars pivoted to opposite sides thereof and adapted to be swung up or down past the conduit to grasp 115 said conduit between them.

3. In combination, in a marble-gun, a conduit, a sighting-standard thereon, and handle-bars pivoted to said conduit and on opposite sides thereof and adapted to be 120 compressed elastically against it to hold it frictionally therebetween.

4. In combination, in a marble-gun, a conduit, a sighting-standard foldably connected thereto, and a pair of handle-bars 125 foldably connected thereto on opposite sides thereof and adapted to be brought together frictionally upon the conduit.

5. In combination, in a marble-gun, a conduit, said conduit having a pair of lugs, 130

a sighting-standard pivoted between said lugs, a pair of handle-bars secured to said lugs and adapted to movably and frictionally seize the conduit between them when 5 grasped, and means for securing releasably said standard in a desired position.

6. In combination, in a marble-gun, a conduit having a pair of lugs, a sighting-standard pivotally mounted between said 10 lugs, and a pair of handle-bars pivoted on opposite sides of said lugs.

7. In combination, in a marble-gun, a conduit having thereon paired lugs, a sighting-standard thereon, a pair of handle-bars located on opposite sides thereof, and means for compressibly holding said lugs, sighting-standard and handle-bars together to retain the standard and the bars releasably in positions in which they may have 20 been placed.

8. In combination, in a marble-gun, a conduit, a sighting-standard thereon, a pair of handle-bars on opposite sides of said conduit and standard, and means for connecting said standard and handle-bars together to retain them in desired positions respectively and releasably.

9. In combination, in a marble-gun, a conduit, and a pair of yieldable resilient 30 handle-bars pivotally connected thereto on opposite sides thereof and bent to conform themselves to the form of the conduit.

10. In combination, in a marble-gun, a conduit, and a pair of handle-bars movably 35 connected to the conduit, and bent to conform themselves thereto and adapted to be swung up past the conduit to lie therealong.

11. In combination, in a marble-gun, a conduit provided with engaging-means in 40 which to secure propelling-means for impelling a missile therethrough, and a pair of elastic handle-bars movably mounted on opposite sides of said conduit and adapted to be moved up or down along the conduit.

45 12. In combination, in a marble-gun, a

conduit, foldable sighting-means thereon, and handles foldably connected to said conduit and adapted in coöperation to act as handles therefor when swung downwardly and compressed upon the conduit toward 50 each other.

13. In combination, in a marble-gun, a conduit, a pair of sighting-standards foldably connected thereto, means for holding said standards in desired positions while 55 permitting restricted movement thereof, and handles pivoted to said conduit to swing over its opposite sides and adapted to be folded upon the conduit.

14. In combination, in a marble-gun, a 60 conduit, propelling-means located at one end thereof, sighting-standards on said conduit foldable toward each other, handles mounted on opposite sides of the conduit and foldable thereupon and means for movably connecting said handles to both the conduit and to one of said standards.

15. In combination, in a marble-gun, a conduit, sighting-standards pivotally connected to said conduit, said standards being 70 so pivoted as to lie the one upon the other, handle-bars pivotally mounted upon the conduit on opposite sides thereof, and means for releasably securing said standards and handle-bars in desired positions. 75

16. In combination, in a marble-gun, a conduit, sighting-standards foldable thereon, handle-bars on opposite sides thereof and also foldable thereon, and a headed body connecting one of said standards and 80 handle-bars to said conduit and adapted to frictionally compress said parts together while permitting restricted movements therebetween.

Signed at Waterloo, Iowa, this 20th day 85 of Sept., 1912.

GEORGE COLVIN KENNEDY.
